UNITED STATES PATENT OFFICE.

CARL BECK, OF VIENNA, AUSTRIA.

SUCKING OR FEEDING BOTTLE.

Application filed March 20, 1925, Serial No. 17,124, and in Austria March 28, 1924.

This invention relates to improvements in sucking or feeding bottles, and its essential feature consists in that the bottle itself is of the shape of a pear with flat sides and that the bottle-neck is disposed laterally and at an incline, and whereby a hole for the reception of a valve is provided in the bottle underneath the bottle-neck.

A further feature of the present invention consists in the particular construction of the valve, as well as in the formation of the side-walls of the bottle.

Compared with similar known arrangements the bottle according to the present invention has the advantage, that only that quantity of air passes automatically into the bottle, which corresponds to the quantity of liquid sucked out of the bottle, whereby it is prevented that the sucking or baby sucks in too much air. Further the liquid cannot subsequently pass into the mouth, as the sucking action is necessary for drawing air into the bottle.

One mode of carrying out the present invention is shown by way of example on the accompanying sheet of drawings, in which.

Figs. 1 and 2 illustrate the feeding bottle in front view and side view respectively.

Fig. 3 shows on an enlarged scale the valve in section.

The body of the bottle *f* is of the shape of a pear with flat sides and the neck is disposed laterally and at an incline. A hole *l* for the reception of a valve *v* is provided underneath the bottle-neck. The valve *v* preferably is made of rubber and consists of a conical member provided with an enlargement or collar *w* above the bottom end and with a passage *o* extending from the preferably flanged end *b* down to the said enlargement *w*, and from the latter down to the bottom end of the valve the latter is provided with a slit *s*. When pressing or forcing the valve into the hole *l* of the bottle, the enlargement or collar *w* of the valve is deformed and after having entirely passed through the said hole, the collar will expand again and take up its original shape, now preventing the valve from dropping out. The air-supply can be regulated by forcing the valve *v* a greater or smaller dis-

tance into the hole *l* of the bottle *f*, whereby the air-passage *o* of the valve is narrowed to a greater or smaller extent. Thus the valve can be adapted to the sucking force of the sucking. Owing to the arrangement of the collar *w*, the valve is properly tightened in the hole *l* of the bottle and further is prevented from dropping out. Owing to the peculiar pear-shaped construction of the bottle, the centre of gravity of the latter is disposed very low, so that the standing conditions and life of the bottle are increased considerably, because the bottle always drops with its bottom onto the floor in case of dropping down and therefore cannot easily break. Depressions *a* for grasping the bottle are provided in the side walls of the bottle near the centre of gravity, so that the bottle can be inclined with ease and its contents can be easily emptied through the inclined neck. The large rounded off corners between the bottom and side walls of the bottle render more difficult the breaking of the bottle and an accumulation of foreign matter or dirt at these places. As shown a graduation or scale may be arranged at one of the walls of the bottle.

I claim—

1. In a feeding bottle, a pear-shaped laterally compressed and obliquely disposed neck which extends towards that side-wall of the bottle on which the latter rests when in use so that the mouth of the bottle assumes the lowest point on this side and the bottle can be sucked quite empty, said body having an opening below the bottle-mouth in the opposite side-wall, and a valve member formed of elastic material and provided with a passage therein fitted in said opening, the said valve member being externally tapered whereby incident to its insertion in the bottle opening, the size of the passage therethrough is varied.

2. A feeding bottle as claimed in claim 1, characterized by the provision of circular depressions provided in the lateral walls at the height of the center of gravity of the bottle.

In testimony whereof I affix my signature.

CARL BECK.
